CLAIM

The ornamental design for a visor, as shown and described.

DESCRIPTION

FIG. 1 is a left side perspective view of a visor showing my new design;

FIG. 2 is a front elevational view thereof;

FIG. 3 is a rear elevational view thereof;

FIG. 4 is a right side elevational view, the left side is a mirror image;

FIG. 5 is a top plan view thereof;

FIG. 6 is a bottom plan view thereof;

FIG. 7 is a left side perspective view of a second embodiment showing my new design, the difference being the rear cylindrical adjusting keeper and the open ends;

FIG. 8 is a rear perspective view thereof;

FIG. 9 is a front elevational view thereof;

FIG. 10 is a rear elevational view thereof;

FIG. 11 is a right side elevational view the opposite side is a mirror image thereof;

FIG. 12 is a top plan view thereof; and,

FIG. 13 is a bottom plan view thereof.

The broken line showing the human form in FIGS. 1, 7, and 8 is for illustrative purposes only and forms no part of the claimed design.

FIG. 1**FIG. 2****FIG. 3****FIG. 4**

FIG. 5
